UNITED STATES PATENT OFFICE.

THEODORE A. HORTON, OF NEW YORK, N. Y.

CASTING APPARATUS.

1,418,078.

Specification of Letters Patent. Patented May 30, 1922.

Application filed July 23, 1919. Serial No. 312,799.

To all whom it may concern:

Be it known that I, THEODORE A. HORTON, a citizen of the United States, and a resident of New York, borough of Manhattan, in the 5 county of New York and State of New York, have invented certain new and useful Improvements in Casting Apparatus, of which the following is a specification.

This invention relates to casting apparatus and its object is to provide means of the class specified, simple in construction and reliable and convenient in operation.

To these ends my improvements comprise features illustrated in their preferred 15 embodiment in the drawing accompanying this specification, wherein:—

Figure 1 is a side cross-sectional elevation on line 1—1 of Fig. 2. Fig. 2 is a front cross-sectional elevation on irregular line 20 2—2 of Fig. 1. Fig. 3 is a section similar to that of Fig. 1 but with some of the members opened out. Fig. 4 is a section similar to that of Fig. 2, also with some of the members opened out. The figures of the drawings 25 are all to one scale.

My improved casting apparatus is for convenience, illustrated as adapted for casting grooved sheaves, and includes base 3 having convenient ears, as 4, 5, 6, upstanding therefrom and in which are carried pivots, as 7, 8. On a portion of these pivots are mounted opposite face members 9 and 10 in the opposing faces of which are formed the 30 contours 11 and 12 of the sheave which the apparatus is designed to produce.

Said members 9 and 10 have their pivot axes in parallelism and so positioned relatively to their bulk, respectively, when said members are in their closed positions, Figs. 40 1 and 2, that the center of gravity of each member will fall between a vertical plane through its pivotal axis, as plane 23 of axis 24, and its face, as 12 of member 10. This arrangement causes said members to lie 45 snugly in their operative positions against score ring sections 13, 14, thus greatly facilitating the operation of the apparatus particularly when heated by use.

Said score ring sections 13, 14 are 50 arranged with their pivotal axes at right angles to those of members 9 and 10 and are similarly pivoted relatively to their bulk, so that when they are in their closed positions 55 of Figs. 1 and 2, the center of gravity of each will fall between vertical plane 25 of

its pivotal axis and its face, as 15 of section 13. One of said face members, as 9, may be provided with a passage for rod 16 to support hub 17 within the mold cavity, onto 60 which to pour the metal for the sheave.

For locking members 9 and 10 securely together in their closed position I preferably employ tiebar 18 in engagement with pins 19, 20 projecting from the upper portions of 65 said members, respectively. Said tiebar may be provided with a central opening 21 for the insertion of block 22 in the mold mouth. Said block is preferably of rectangular pyramidal form and is efficient for 70 dividing the stream of metal into two streams as it flows into the mold and for choking those two streams into fine jets to the exclusion of dirt and flotsam. 75

I claim:

1. In casting apparatus the combination of two pairs of opposite pivoted members, each pair disposed at right angles to the other pair, one pair of said members closing into coactive engagement and the other pair closing into coactive engagement with the first mentioned pair, respectively, each of said members of each pair having its center of gravity between a vertical plane through its pivotal axis and that face thereof which coacts with another one of the members. 80

2. In casting apparatus the combination of two pairs of opposite coacting members, each member being cut away at the point of conjunction of the four members for forming a mold mouth and a removable block for insertion in said mold mouth for providing opposite narrow channelways for the 85 inflowing metal. 90

3. In casting apparatus the combination of a plurality of coacting members, each of said members being cut away at its upper point of coaction for forming a mold mouth, 100 and a removable rectangular block for insertion in said mold mouth, having one pair of opposite sides in contact with said mold mouth and the other two sides forming walls, respectively, for coaction with the 105 mold mouth to form two passages into said apparatus and to choke those passages.

4. In casting apparatus the combination of a pair of opposite pivotally mounted mold members folding together into coacting 110 relation, and a second pair of opposite pivotally mounted mold members folding

into coacting relation with each other and with the first mentioned pair of members, said second pair of members being pivoted at right angles to the pivoting of the first 5 mentioned pair of members.

5. In casting apparatus the combination of a pair of oppositely disposed mold members each pivotally mounted independent of the other on axially parallel pivots for folding 10 into coacting relation, and a second pair of mold members each pivotally mounted independent of the other on axially parallel pivots for folding into coacting relation with said first pair of members and with each 15 other, the axes of the pivots of the first pair of members being disposed at right angles to the axes of the pivots of the second pair of members.
6. In casting apparatus the combination 20 of two pairs of opposite coacting members one member of one pair being cut away at the point of conjunction of the four members for forming a mold mouth, and a removable block for insertion in said mold

mouth for providing a plurality of narrow 25 channelways for the inflow of metal.

7. In casting apparatus the combination of a plurality of coacting members, each of said members being cut away at its upper point of coaction for forming a mold mouth, 30 and a removable block for insertion in said mold mouth having opposite portions in contact with said mold mouth and other opposite portions forming walls, respectively, for coaction with the mold mouth to 35 form passages into said apparatus and to choke those passages.

8. In casting apparatus the combination of two pairs of opposite pivoted members, each pair disposed at right angles to the other pair, one pair of said members closing 40 into coactive engagement and the other pair closing into coactive engagement with the first mentioned pair.

In witness whereof, I hereby affix my 45 signature this 17 day of July, 1919.

THEODORE A. HORTON.
